To all whom it may concern:

Be it known that I, Irving Hirschman, a citizen of the United States, residing at Brooklyn, in the county of Kings and State of New York, have invented a new, original, and ornamental Design for a Pair of Spectacles or Similar Article, of which the following is a specification, reference being had to the accompanying drawing, forming a part thereof.

Fig. 2 is a top plan view thereof.

Fig. 3 is a side view thereof.

Fig. 4 is a fragmentary side elevational view, on an enlarged scale, of a portion of the full line showing of one of the temples, the same being typical of the full line showings of the lens rims.

The dominant feature of the design resides in the portion shown in full lines.
